HAIR WAVING DEVICE

Maurice Serre, Astoria, N. Y., assignor of one-half to Guy de Leyer, Boston, Mass.

Application January 12, 1935, Serial No. 1,507

10 Claims. (Cl. 132—33)

My invention relates to hair waving apparatus, and more particularly to hair waving elements or clips for use on hair waving devices known as "croquignole permanent wave machines".

Clips used for this type of machine are at present so constructed, that the strands of hair can be rolled or curled under only. Moreover, the curler rod can not be locked at any point frequently necessitating the strand of hair to be partly unrolled, until the locking point for the curler rod is reached. Also, on the clips now in use, the clip locking device is so located, that when the clips are placed in position on the head, it is most difficult, during the waving operation, to remove any of the clips, if for any reason this should become necessary.

Furthermore, the clips now in use have many metal parts permitting the transmission of heat and in some cases also resulting in short circuits, electric shocks, etc., aside from the fact that metal in certain cases causes discoloration of the hair.

One object of the present invention is to make a clip in which for the curler rod there is provided a ratchet-like hook, which can be swung to either side permitting the rolling and curling of the hair either over or under, which is especially useful in the waving of the hair around the neck.

Another object of my invention is to produce a clip providing for the positive and automatic locking of the curler rod onto the clip at any desired point at which the curler rod is placed on the clip.

Another object of my invention is to produce a clip which can be locked both laterally and longitudinally and in which the lock is operated from the top of the clip, thereby permitting the easy removal of any clip during the waving operation. In addition thereto, the clip is locked by the curler rod, which, when in place, effectively prevents the opening of the clip.

Furthermore, in my new clip the notches on the curler-rod are so constructed as to permit hooking of the ratchet-hook in either direction, to wit, whether the hook is placed for rolling the hair over or under. Also, a second ratchet wheel may be provided at the other end of the curler-rod.

Another object of my invention is to eliminate from the clip as well as the curler-rod the metal by the substitution therefor of a heat-insulating composition, e. g. bakelite, whereby not only the transmission of heat to the scalp of the customer is decreased to a minimum, but also short-cir-

cuits and electric shocks both to the operator and the customer are prevented. In addition thereto, I provide air spaces and ventilating apertures both for better heat insulation and for the dissipation of the heat.

Moreover, my new clip is of low construction so as to permit the rolling and the curling of the hair closer to the scalp than is possible with the clips now used.

Other new features will appear from the following detailed description of my invention with reference to the appended drawings, on which I have shown a preferred embodiment of my new clip and curler rod and on which

Fig. 1 is a perspective view of the new clip with a strand of hair shown clamped between the two jaws of the clip; Fig. 2 is a perspective view of the curler-rod; Fig. 3 an end-view of the clip with the curler-rod in place thereon; Fig. 4 is a top plan view of the clip with the curler-rod in place thereon, showing a strand of hair wound on the rod; Fig. 5 is a perspective view of the "key" used for the turning of the curler-rod; Fig. 6 is a fragmental view of the clip showing part of the lock therefor; Fig. 7 shows the clip with its jaws separated; Fig. 8 is a central longitudinal section through the clip and curler-rod; Figs. 9, 10 and 11 are transverse sections respectively along lines 9—9, 10—10 and 11—11 in Fig. 8. Fig. 12 is a longitudinal section through a modified curler-rod. Fig. 13 is a view of a detail partly in section.

On the drawings, the clip as a whole is designated A. It comprises two jaws 1 and 2 of rectangular shape, which jaws at one end of the clip are hinged together as follows: The jaw 1 is provided at one end with a cross-piece shown at 3 in Fig. 7, to which cross-piece the other jaw is hinged as shown at 4 in said figure. At the other end of jaw 1 there is hinged thereto at 5 a cross-piece 6 which in a slot provided therein carries a locking finger shown at 7, said finger being pivoted in said slot, so that it can be swung toward either end of said cross-piece. At 8 there is shown an opening in said cross-piece adapted to receive a catch-pin shown at 9, when the cross-piece is moved against the ends of the two jaws after the same have been closed. On the lower end of the locking finger 7, there is provided a lug shown at 10 in Fig. 9, which lug, as the locking finger 7 is swung into the full-line position in Fig. 9, engages the catch-pin 9 thereby locking the cross-piece to the jaw 2 and thus locking the two jaws together. To release the jaws, the locking finger is swung into the broken line posi-

tion in Fig. 9, in which position the lug 10 will be disengaged from the catch-pin 9.

The two jaws 1 and 2 are made of a heat insulating composition, e. g. bakelite, whereby not only the transmission of heat is decreased to a minimum, but, since the said material also has a high dielectric strength, protection is afforded thereby against possible short-circuits and electric shocks. Moreover, the said material is light, and practically no weight will be felt when the clips are placed on the head of the customer. At 11 are shown air spaces, which, besides being poor heat conductors, also constitute ventilating apertures for the dissipation of the heat generated by the heating elements (not shown). The two jaws are grooved to receive strips 12, of rubber, or other elastic material, for gripping the strand of hair without causing injury thereto. On the slightly concave bottom, the jaws are provided with a thin layer of felt, or the like, shown at 13 to prevent any unpleasant pressure of the clip against the scalp and to provide additional heat insulation.

On the outside of the hinged cross-piece 6, 25 there is provided a spring clamp shown at 14, which at its upper end carries a hook-shaped pin 15 adapted to enter a depression provided in one end of the curler rod 16, as the latter with a strand of hair wound thereon is placed in position on the clip.

As shown in Fig. 9, there is provided in the slot of the cross-piece 6 at 17 a small spring designed 35 to hold the locking finger 7 in place in either its full-line or broken-line position.

In a slot in the stationary cross-piece 3 carried by the jaw 1 there is provided a ratchet lever shown at 18, which with its lower end is pivoted in the center of said cross-piece so that it can be swung to either side thereof.

At 19 in Fig. 11 is shown a curved spring 40 adapted to be engaged by the tail-piece 20 of said ratchet-lever, so that the latter will be held in either its full-line or broken-line position, both as shown in Fig. 11. At or near its upper end, 45 the lever 18 carries on opposite sides each a ratchet-tooth 21 and 22 respectively. These ratchet-teeth, when the curler-rod with a strand of hair wound thereon is mounted on the clip, are designed to engage any of the notches provided in the manner of a ratchet-wheel on one 50 end of the curler rod, as shown at 23 in the drawings. These notches, 23, are so constructed as to permit engagement by the ratchet-hooks 21 or 22 in either direction, to wit, whether the 55 ratchet-like hook 18 is placed for the hair being rolled up or down. Moreover, the notches are placed so close together, that the curler-rod will be effectively locked at any point, at which it is placed on the clip without the necessity of the hair being partly unrolled.

If desired, a second "ratchet-wheel" may be provided on the other end of the curler-rod, as shown in Fig. 12, which facilitates the handling of these rods by the operators.

As shown on the drawings, the two ends of the curler-rod are made larger than the diameter of the bearing portions of the rod so as to prevent any accidental, longitudinal displacement of the rod. The two ends, as shown more clearly in Fig. 2, are preferably of a geometrical design, e. g. a hexagon, as shown at 24 in said figure, onto which may be fitted a correspondingly designed key shown at 25 in Fig. 5. These hexagon-shaped ends are slightly bevelled on the inside,

as will appear from Fig. 4, which facilitates the rods being placed in position on the clip.

The key 25 is used, after the curler-rod with a strand of hair wound thereon has been placed on the clip, to impart to the rod an additional slight turn so as to tighten the hair. This is possible because of the close intervals between the ratchet teeth 23 on the curler-rod, which arrangement permits the locking of the curler-rod at practically any point. 10

It will be seen that the curler-rod, after having once been placed in position on the clip is positively and automatically locked in that position, that is to say, at one end by the ratchet lever 18, engaging with one of its ratchet-hooks the 15 ratchet-teeth on the curler-rod and at the other end by the spring-clip 14 engaging with its hook 16 the other end of the rod.

The clip, because of its low construction, permits the winding and the curling of the hair 20 closer to the scalp than is possible with the clips now in use, aside from its other improved features, whereby its sturdiness, safety and reliability as well as easy handling are considerably increased. 25

While I have described and shown a preferred embodiment of my invention, it is obvious, that this construction is capable of various modifications without a departure from the essence of my invention, and, therefore, I do not limit myself to the construction as shown. 30

I claim:

1. In a hair-waving device, the combination of a curler-rod provided with a series of circumferentially arranged depressions, a hair-gripping clip designed to receive said curler-rod, and means on said clip pivotally mounted thereon so as to be capable of engaging the depressions on said curler-rod from either side thereof. 35

2. In a hair-waving device, the combination 40 of a curler-rod provided with a series of circumferentially arranged depressions, a hair-gripping clip designed to receive said curler-rod, means on said clip pivotally mounted thereon so as to be capable of engaging the depressions on said 45 curler-rod from either side thereof, and a spring-actuated hook on said clip for engaging the other end of said curler rod.

3. In a hair-waving device, the combination of 50 a curler-rod provided with a series of circumferentially arranged depressions, a hair gripping clip designed to receive said curler-rod, means on said clip pivotally mounted thereon so as to be capable of engaging the depressions on said curler-rod from either side thereof, and means 55 for locking said depression engaging means in position.

4. In a hair-waving device, the combination 60 with a curler-rod adapted for a strand of hair to be wound thereon, of a clip adapted to receive said rod and comprising two elongated jaws hinged at one end to each other and adapted to be folded against each other to grip therebetween a strand of hair, a catch-pin projecting from the end of one of said jaws, a cross-piece pivoted to 65 the end of the other jaw and provided with an opening for receiving said catch-pin, and a finger pivotally mounted in said cross-piece upwardly projecting therefrom and designed to be moved into locking engagement with said catch-pin thereby locking the said two jaws together. 70

5. The combination as specified in claim 4, including a means for holding said finger in locking engagement with said catch-pin.

6. In a hair-waving device, the combination 75

5 with a curler-rod adapted for a strand of hair to be wound thereon, of a clip designed to receive said rod and comprising two elongated jaws hinged at one end to each other to be folded against each other to grip therebetween a strand of hair, a cross-piece pivotally carried by one of said jaws, mutually engaging locking means provided in said cross-piece and the end of the other jaw, and a spring-actuated hook carried by said cross-piece for engaging one end of said curler-rod.

10 7. In a hair-waving device, the combination with a curler-rod adapted for a strand of hair to be wound thereon, of a clip designed to receive said rod and comprising two elongated jaws of dielectric material and of small height and formed with ventilating openings therein, said two jaws being hinged at one end to each other to be folded against each other to grip therebetween a strand of air, a cross-piece pivotally carried by one of said jaws, mutually engaging locking means provided in said cross-piece and in the end of the other jaw, and a means for holding said locking means in locking position.

15 8. The combination as specified in claim 7, in which the bottom portions of said jaws are designed to form a slightly concave bottom of the

clip, including a layer of felt, or the like, covering said bottom portions.

5 9. In a hair-waving device, the combination of a curler-rod adapted for a strand of hair to be wound thereon and provided at either end with a series of circumferentially arranged depressions, a clip designed to receive said curler-rod with the hair wound thereon and comprising two elongated jaws hinged to one another and adapted for gripping therebetween a strand of hair 10 close to the scalp, a lever fulcrumed at one end of said jaws in a central position being capable of being swung into operative position to either side of said clip, said lever having on opposite sides a ratchet hook adapted to engage any of the 15 depressions on said curler-rod for locking it in position on said clip, and a bent spring cooperating with said lever for holding the same in its locking position.

10 10. The combination as specified in claim 9, 20 including means for locking together the said two jaws when folded together, and a spring-actuated hook adapted to automatically engage one end of said curler-rod as the latter is placed 25 in position on said clip.

MAURICE SERRE.
